United States Patent Office

Des. 225,457
Patented Dec. 12, 1972

225,457

COMBINED PHONOGRAPH TURNTABLE, BASE, AND CASSETTE PLAYER OR SIMILAR ARTICLE

Lawrence Levow, Huntington, N.Y., assignor to Harman-Kardon, Incorporated, Plainview, Long Island, N.Y.

Filed Oct. 15, 1969, Ser. No. 19,578

Term of patent 14 years

Int. Cl. D14—01

U.S. Cl. D56—4

The single figure is a front and top perspective view of a combined phonograph turntable, base, and cassette player or similar article showing my new design, the base having substantially the same appearance from the rear and both sides.

I claim:

The ornamental design for a combined phonograph turntable, base, and cassette player or similar article, as shown and described.
